TOGGLE SWITCH

William L. Butler, Schenectady, N. Y., assignor to
 Weber Electric Company, Schenectady, N. Y.,
 a corporation of New York

Application January 8, 1931, Serial No. 507,473

12 Claims. (Cl. 200—67)

This invention relates to new and useful improvements in snap or toggle switches.

An important object of the invention is to provide a switch of the above type in which vibration of the switch blade is reduced to the minimum consistent with economy of manufacture. Switches of the type now in general use on heavy loads of incandescent electric lamps, possess switch blades subject to vibration which causes excessive arcing, thereby resulting in detrimental effects upon the switch blade and the stationary contacts with which it cooperates. The vibration of the switch blade occurs only for a small fraction of a second when the switch is thrown to "on" and "off" positions and is most detrimental when the switch is turned to an "on" position due to the fact that the resistance to the current offered by the incandescent lamps in circuit with the switch is comparatively low when the lamp filament is comparatively cool or at room temperature, thereby permitting a greater flow of current through the switch during this interval and until the filament becomes heated and creates more resistance to the current. The first inrush of current to these lamps has been found to be as much as fifteen times the normal value. Consequently, vibration of the switch blade at this time results in arcing between the contacts which burns and pits the same to such an extent that their life is greatly reduced. It is, therefore, the primary object of the invention to reduce the vibration of the switch blade to the minimum.

Another important object of the invention is to arrange the stationary contacts in such a manner to quench any sparks resulting from any possible arcing between the same and the movable switch blade.

Another important object of the invention is to provide an arrangement in which the switch blade can be constructed comparatively thick and substantially unyielding, whereby its life may be increased; such blade being normally urged to a position to efficiently engage the stationary contacts by means of a structurally separate spring element. Due to the spring element being structurally separate from the switch blade, the latter is not subjected to the annealing effects of any arcing between the switch blade and the stationary contacts.

A still further object of the invention is to cause the ends of the movable switch blade to directly engage the walls of the insulated support as it moves to "on" and "off" positions whereby the blade is wiped and kept clean.

Other objects and advantages of the invention will become apparent during the course of the following description.

In the accompanying drawings, forming a part of the description, wherein like numerals are employed to designate like parts throughout the several views; and wherein those parts of the device bearing reference numerals with coefficients throughout the several views correspond to the parts bearing the basic or plain identifying numerals, except where otherwise noted.

Figure 1 is a top plan of a toggle switch embodying the invention.

Figure 2 is a longitudinal vertical section through the insulator casing showing the stationary contacts in position.

Figure 3 is a scattered view of parts of the switch constituting certain improvements in the present invention and showing the switch blade and associated parts in perspective with a sectional perspective view of a wall of the switch casing with which the switch blade cooperates.

Figure 4 is a top plan of a switch showing a modified form of switch blade associated therewith, and

Figure 5 is a fragmentary top plan of a modified form of casing.

Figure 6 is a top plan of a switch embodying another form of switch blade.

Figure 7 is a scattered view of parts of the switch shown in Figure 6, showing the switch blade and associated parts in perspective with a sectional perspective view of a modified wall construction.

Figure 8 is a perspective view of a modified form of switch blade.

Figure 9 is a sectional perspective view of another modified form of wall, and

Figure 10 is a similar view of still another form of casing wall.

Referring now more particularly to the drawings for a detailed description of the various parts of the invention, the numeral 5 designates a switch casing which may be constructed from any suitable insulating material such as porcelain or the like.

This casing or support has as usual, a cavity 6 which opens out into the top of the casing as is customary in this art, to receive and house a snap toggle mechanism such as disclosed in my copending application Serial No. 231,059. This toggle mechanism includes a crank or rocker 7 of U-shaped form having trunnions 8 and 9 projecting in opposite directions from the two arms thereof for pivotal support in V-shaped recesses 55

10 provided in opposite side walls 11 of the switch casing 5. This crank 7 may be stamped from any suitable sheet material of metal or insulating material depending upon the manner desired for insulating the switch blade from the mechanism. 5 The bridge portion 12 of the rocker 7 is equipped with a projection 13 adapted to enter the end of a compression coil spring, not shown, the other end of the spring being connected to the lower 10 end of an operating lever 14 pivotally mounted in a bridge piece 15 spanning the cavity 6 in the casing and secured to opposed walls thereof by the usual screws 16 extending from the back of the casing. As is well understood in the art, movement of the operating lever 14 upon its axis, causes the coil spring to be compressed and moved across the axis of the crank 7 thereby impelling the same 15 from one position of rest to another with a quick snap action. As a general description of this 20 toggle mechanism is sufficient for a comprehensive understanding of the present improvements, an illustration of the details thereof has been omitted.

As is customary in this type of switch, a pair of 25 stationary contacts 17 and 18 are provided at opposite ends of the casing 5, one at the bottom of the cavity in the casing and the other at the top thereof as best shown in Figure 2. These contacts are, of course, provided with the usual 30 binding posts 19 for connection of the wiring thereto. Unlike present arrangements, the contacts are positioned directly against a side wall of the casing, instead of being spaced therefrom in the customary way.

35 In Figure 3, a side wall 11 of the casing or support against which the stationary contacts are disposed, is provided with a central depression or recess 20, the sides of which are defined by slightly raised flat surfaces 21 and 22 having arcuate edges as shown. The raised surface 21 terminates 40 short of the bottom of the cavity to provide a shallow recess 23 communicating with the central recessed portion 20 for the reception of the contact portion of the stationary contact 17. This contact is arranged adjacent the bottom of the cavity and is provided with a vertical extension which extends up along one end wall as shown in 45 Figure 2 to terminate in the angularly disposed end having the binding post 19 associated therewith. The elevated portion 22 at the opposite side of the central recess 20 terminates short of the top of the casing 5 to provide a second shallow recess 24 for the reception of the contact portion of the stationary contact 18. These two recesses 50 23 and 24 are preferably comparatively shallow and are of a depth of approximately one-half the thickness of the contact portions of the stationary contacts seated therein. This arrangement permits of seating approximately one-half the thickness 55 of the contact portions of the stationary contacts in the shallow recesses so that the other half of the thickness of the contact portions projects slightly beyond the elevated surfaces 21 and 22 of the casing as best seen in Figures 1 and 4. 60 If desired, the shallow recesses 23 and 24 may be entirely eliminated and the contact portions of the stationary contacts secured directly against a plain flat wall, but this necessitates allowance of more play in the mounting of the switch blade as 65 will be more fully described hereinafter.

70 As shown in Figure 3, the bottom of the cavity is equipped with a pair of depressions 25 to alternately accommodate the ends of the switch blade in its "on" and "off" positions. In a double pole 75 or three point switch, the opposed side walls 11

of the casing are formed to correspond with the construction of the side wall just described for the accommodation of a second pair of stationary contacts not shown.

The crank 7 being formed from flat sheet material causes its trunnions 8 and 9 to possess a substantially rectangular cross section. The trunnion 8 which may be shorter than its brother when used in conjunction with a single pole switch, is bevelled to terminate in substantially a sharp point 26 for a purpose which will presently appear. Both trunnions are equipped on the upper edge with an abutment projection 27 in both modifications shown in Figures 1 and 4. The trunnion 8 forms a mounting for a switch 15 blade 28 having a pair of arms 29 projecting in opposite directions and terminating in winged contact ends 30. The central portion of this blade is provided with a rectangular opening 31 to receive the trunnion 8. This opening 31 may be 20 of a size to slidably fit the trunnion or it may be slightly larger to permit a looser fit thereon when the stationary contacts project the full thickness 25 of their material from the face of the side wall 11. In any event, it is of a size whereby the switch 25 blade may be easily moved on or off of the trunnion 9 without the use of tools.

Heretofore, switch blades in this type of switch have been constructed of light springy conductive material due to former arrangements of the stationary contacts, but such switch blades are short lived due to excessive pitting caused by arcing at the contact ends. In the present improvements, the switch blade 28 may be constructed of rigid and heavier conductive material not necessarily 35 possessing inherent resilience due to the provision of a resilient element 32 normally urging the switch blade toward the wall of the casing carrying the stationary contacts. This spring element is structurally separate from the switch blade and 40 may assume various forms, but is here shown in the form of a flat spring constructed from any suitable material. The spring 32 is provided with a central rectangular aperture 33 for loose mounting upon the trunnion 9 of the crank in engagement with the abutment shoulder 27. This spring blade 32 is provided with a pair of arms 34 extending in opposite directions from the center, which arms have their outer terminals 35 angularly disposed for engagement with the arms 29 of 50 the switch blade adjacent their outer ends. The extent of the angularly disposed ends 35 of the spring is determined by the distance between the shoulder 27 of the crank and the elevated surfaces 21 and 22 of the casing and is such as to normally 55 press the switch blade toward the cavity 28 to span the same with the contact ends 30 of the switch blade forced into engagement with the elevated plane surfaces 21 and 22 of the side wall, or the two stationary contacts depending upon 60 the position of the crank 7. This action of the spring 32 naturally stresses the crank in the direction of its axis and toward the opposite side wall of the casing. It is for this reason that the end 65 of the trunnion 8 is bevelled into a point so as to reduce friction between the crank and the side wall of recess 10. It will also be apparent that the spring blade 32 also stresses or urges the switch blade 28 in the direction of the axis 70 of the crank 7 and toward the side wall carrying the stationary contacts so as to firmly press the contact ends 30 of the switch blade in engagement with the stationary contacts when the toggle mechanism is operated through the actuating 75

lever 14 to complete a circuit in which the switch is included.

Assuming that the switch is in an "off" position with the switch blade out of engagement with the stationary contacts 17 and 18, and it is desired to turn the switch on, the operating lever 14 is swung upon its axis causing the rocker 1 to be swung on its trunnions 8 and 9 with a rapid snap movement induced by the toggle spring being moved across the axis of the rocker. The contact ends 30 of the switch blade 28 being urged into engagement with the elevated surfaces 21 and 22, are also caused to rapidly move to positions of engagement with the stationary contacts, but with a slightly retarded action due to the friction set up between the same and elevated portions 21 and 22. The retardation, however, is not sufficient to permit arcing between the blade and stationary contacts, but is just enough to reduce vibration of the blade during its movements. This has been found advantageous, since a very rapid movement of the blade tends to increase vibration and consequently arcing when it jumps up against the stationary contacts. With the switch blade stressed toward the wall carrying the stationary contacts in the above manner, no interference with the successful interruption of the arc when the switch is turned off is experienced, since the presence of the edges of the recesses 23 and 24 directly in the path of the arc, help to quench it. In this connection, it has been found desirable to maintain the contact surfaces of the stationary contacts slightly beyond the elevated surfaces 21 and 22 as this permits the switch blade to move more rapidly off of the contacts when moving to an "off" position. The movement of the contact ends 30 of the switch blade over the elevated portions 21 and 22 sets up a slight abrasive action, especially when porcelain is employed in the construction of the casing, to wipe the contact ends of the blade and maintain them in a clean condition. Due to the fact that the spring element 32 is structurally independent of the switch blade, it is removed from any possibility of being affected by any annealing heat present in the ends of the switch blade and permits of the switch blade being made of a very heavy and rugged construction.

In the event that the recesses or sockets 23 and 24 for the stationary contacts are eliminated and the contact portions of these stationary contacts are placed directly against the plane surface of the side wall 11' as shown in Fig. 5, so that they project the full thickness of the metal from the face of the side wall; it is necessary for the switch blade 28' to have more lateral play, so that it can get up onto the stationary contacts 17' and 18'. This may be accomplished by forming the mounting aperture 31 slightly larger than the cross sectional shape of the trunnion 9 to provide a floating connection of the switch blade with the crank or rocker giving it the necessary increased lateral movement. In such construction as shown in Fig. 5, the arrangement and construction of the spring 32' is such as to exert sufficient stress upon the switch blade 28' as to force it against the stationary contacts, but not sufficient to force the blade into engagement with the wall 11' when the blade is in an "off" position. Thus, in this modification, the frictional contact between the switch blade and wall 11' is eliminated.

It will be evident, that if desired, the switch blade may be assembled rigidly with the rocker or crank, or made integral with it, and a spring ele-

ment 32 of suitable design provided which would act upon the switch blade or crank to force the crank or rocker 1 and contact blade assembly toward the wall on which the stationary contacts are assembled. This, obviously, would necessitate the allowance of slight axial movement of the crank. When a double pole switch is provided as stated hereinbefore and a second switch blade assembly is mounted upon the trunnion 8, the action of the switch will be the same except that an additional spring element 32 would be provided on the trunnion 8 which would oppose the spring element 32 on the opposite end of the rocker and would balance the tendency of the rocker to move in the direction of its axis in either direction. In this arrangement the end of the trunnion 8 can be pointed similar to the end 28 so as to reduce any possible friction should the urge of one spring element be stronger than the other.

To turn the switch off, the operating lever 14 is moved in the opposite direction on its pivot to cause the rocker to swing on its axis and move the switch blade 28 off of the stationary contacts 17 and 18. In this movement of the switch blade, its contact ends 30 have accelerated movement in leaving the stationary contacts due to the latter being arranged beyond the elevated surfaces 21 and 22. After the contact ends 30 of the switch blade leave the stationary contacts they are forced into engagement with the elevated plane surfaces 21 and 22 by the spring element 32 in the form of invention shown in Fig. 1, where they are wiped and cleansed in their action of rubbing over the elevated surfaces, but in the form shown in Fig. 5, the contact blade 28' is not so forced into engagement with the wall 11' as hereinbefore explained.

In Figure 4 another modification of the invention is illustrated which is identically the same as the preceding Figure 1, except for the construction of the switch blade. In this instance, the switch blade 36 is illustrated as being a relatively thin piece of resilient conductive material having its intermediate portion 37 bowed to impart resilient flexibility thereto. This type of switch blade does not necessitate the use of a separate spring element such as 32 in the preceding embodiments, due to the fact that it is inherently resilient. However, this switch blade 36 is provided with the same kind of aperture 31 as in the preceding modification for association with the trunnion 9 of the rocker so that it abuts the stop shoulder 27 on the rocker when the contact ends of the switch blade are arranged in engagement with the stationary contacts 17 and 18. When in "off" position, this switch blade 36, may or may not be urged against the side wall of the casing, but it is essential that it be stressed against the stop lug 27 of the rocker when its contact ends are arranged in engagement with the stationary contacts, to establish a sound electrical connection and to reduce vibration of the blade and consequent arcing.

In Figures 6 and 7, further modifications of the invention are shown and consist essentially of the formation of a one-piece rocker and switch blade and the construction of the wall of the casing toward which the switch blade is normally urged by reason of the inherent resilience of the rocker or a structurally separate spring element, such as described in connection with the form of invention shown in Figure 3. As stated previously those parts of the modification bearing reference numerals with coefficients correspond with previously described parts bearing basic or plain refer-

ence numerals, except where otherwise noted, and consequently such parts will not be described in detail.

As particularly shown in Figure 7, the wall 11a of the casing toward which the contact blade is normally urged, is equipped with inclined or tapered elevated surfaces 21' and 22', which inclinations gradually increase toward the recesses 23a and 24a respectively, so that the elevated portions are in effect reversely inclined toward the bottom and top of the casing. These inclined portions provide counter-sinks for the contact portions 17 and 18 of the stationary contacts and as will be noted in Figure 6, the contact surfaces of the contact portions of the stationary contacts protrude a distance equal to substantially one-half the thickness of the contact portions, beyond the highest portions of the inclined surfaces 21' and 22'. Of course, if desired, the contact portions of the stationary contacts may be arranged at a greater distance from the elevated portions or flush therewith, as may be desired. The purpose of the elevated inclined surfaces is to retard the snap action of the switch blade in progressively increasing amplitude as the blade approaches the stationary contacts.

The oscillatory rocker 12a, shown in Figures 6 and 7, is of especially novel formation, in that the switch blade 29a with its guide wings 30a are formed as an integral part of one end of the rocker. This unit is preferably constructed of conductive sheet metal and may be of a gauge rendering the switch blade substantially rigid to ably withstand the detrimental effects of any arcing which may occur between the same and the stationary contacts. This material is also preferably of a gauge which, when bowed or bent into the U-shaped formation shown, imparts certain resilient characteristics thereto, whereby the arms of the U-formation possess sufficient resilience to normally be urged outwardly toward opposed side walls of the casing and to thereby normally urge the switch blade 29 toward the wall 11a of the casing carrying the stationary contacts, but not to a sufficient degree to cause engagement of the switch blade with said wall when the switch is in an "off" position. However, the arms of the rocker are normally stressed sufficiently to cause the switch blade to engage the inclined elevated surfaces 21' and 22' in progressively increasing amplitude as they move toward the stationary contacts and after they have engaged the same are firmly pressed by the resilience of the rocker into a firm electrical contact.

The arch portion of the rocker is provided with an up-struck lug 13a, which like the lug 13 of the form of rocker shown in Figure 3, is adapted to engage with one end of a compression spring, such as is common in the art. A trunnion 8a is formed integral with one of the arms of the rocker by cutting the arm transversely and bending the cut portion outwardly of the arm to extend in a plane at substantially right angles with the plane of the upright portion of this arm. This trunnion is preferably bevelled as at 26a to reduce the amount of friction between the rocker and casing at the point where the trunnion engages with its V-shaped seat 10a in the side wall.

The other trunnion or mounting portion 9a is also formed integral with the combined rocker and switch blade by cutting the material along three lines at the medial portion of the switch blade and bending the cut portion outwardly, so that it, like the trunnion 8a, extends in a plane at right angles to the plane of the switch blade

to engage in a V-shaped seat 10a in the opposite side wall of the casing. If desired, this trunnion 9a may be clipped to provide it with a bevelled upper edge corresponding with and for the same purpose as the bevel 26a. With this construction, it will be evident that the more or less pointed ends of the mounting portions 8a and 9a will be stressed into engagement with the opposed walls of the casing, so as to normally urge the switch blade 29a toward the wall bearing the stationary contacts.

In the event of it being desirable to form the combined rocker and switch blade from sheet metal which is substantially rigid and unyielding, this may be accomplished without sacrificing any of the desirable attributes of the construction just described by providing a spring element 32a, corresponding in purpose to the spring element 32 of the form of invention disclosed in Figure 3. This spring element in this instance may be provided with an enlarged circular aperture 33a of a diameter slightly in excess of the height of the trunnion 8a, to loosely receive the same so as not to be rocked with the oscillations of the rocker. In this instance, the ends 35a of the flat spring element are bowed outwardly toward a side wall of the casing to engage the same and to cause the entire rocker with its integral switch blade 29a to be normally urged toward the wall of the casing having the stationary contacts. The operation of this modified construction of the device is in general the same as that device described in connection with Figure 1.

In the event that it is not desired to form the elevated portions of the side wall 11 integral therewith, as in the preceding modifications, they may be formed as separate pieces of flat insulating material 21b and 22b, Figure 10, slid into grooves 38 provided in the side wall 11b at opposite ends thereof and an opening out through the 40 terminal seats, as shown. The piece 21b, as shown, is provided with a laterally extending portion which is adapted to abut the shoulder 39 beneath the terminal seat to limit the downward movement and to space the lower edge of the insulating piece in the bottom of the casing to provide a recess 23 for the stationary lower contact 17. The insulating piece 22b extends all the way down to the bottom of the casing, as shown, and its upper edge is substantially flush with the 50 terminal seat. The upper edge of the lateral projection on the piece 21b, likewise is flush with its terminal seat, so that when the terminals are assembled with the casing, they effectively retain the insulating pieces in proper position. The 55 arrangement of the stationary contacts with respect to these insulating pieces may be the same as disclosed in conjunction with the preceding forms of the invention.

In Figure 9, a modification of the side wall construction is disclosed in which the entire surface of this wall with which the contact blade is normally engaged, is capped or surfaced with a flat piece of insulating material 40 shaped, with its two ends received in grooves, such as shown in Figure 10, and in the same manner as disclosed therein, so that the terminals of the stationary contacts will effectively retain this sheet of insulation in proper position. The piece 40 is equipped with a V-shaped notch 41, corresponding to the contour of the V-shaped seats 10c in side walls 11c to register therewith and if desired, these V-shaped edges of the notch 41 may be spaced slightly above the corresponding portions of the recesses in the casing 5, so as to 75

form the sole support of the rocker without assistance from the side walls of the casing. Any of the switch blades heretofore described may be used in connection with the construction shown in Figure 9, but preferably a blade such as shown in Figure 8 is used and which has its ends 30b offset as at 42.

From the foregoing it will be apparent that any suitable construction may be provided for the operating mechanism for carrying out of the various functions in the modifications as hereinbefore disclosed. It is also to be understood that various changes in the construction and arrangement of the other parts of the device may be resorted to without departing from the scope of the appended claims.

I claim:

1. In a snap switch, a support having a wall, stationary contacts, an actuating mechanism, a switch blade operated thereby and arranged with its ends urged toward said wall, and reversely arranged inclined blade engaging pieces positioned adjacent said contacts and inclined in progressively increasing degrees toward said contacts.
2. In a snap switch, a support, a pair of stationary contacts carried by a wall thereof, an actuating mechanism including a rocker and an oscillatory switch blade operable by said rocker, and a spring blade structurally separate from the switch blade mounted upon said rocker and having deflected ends engaging the switch blade adjacent its ends to normally urge the same into engagement with said wall of the support, the wall serving to guide the switch blade ends toward and away from the contacts.
3. In a snap switch, a support, a pair of stationary contacts carried thereby, an actuating mechanism including a rocker having an axially extending arm, a switch blade mounted on said arm and extending transversely thereof for cooperation with said contacts, and a resilient member structurally separate from said blade engaging said rocker for normally urging the same axially and the switch blade toward the contacts.
4. In a snap switch, a support, a pair of stationary contacts carried thereby, an actuating mechanism including a rocker having a lateral arm provided with a shoulder, a switch blade mounted on said arm for cooperation with said contacts, and a flat spring structurally separate from the switch blade engaging the shoulder to normally urge the blade in the direction of the axis of the rocker and toward the contacts.
5. In a snap switch, a support, a pair of stationary contacts carried thereby, an actuating mechanism including a rocker having a lateral arm provided with a shoulder, a switch blade mounted on said arm for cooperation with said contacts, and a spring blade structurally separate from the switch blade mounted upon said rocker in engagement with said shoulder and having deflected ends engaging the switch blade adjacent its ends to normally urge the same in the direction of the axis of the rocker and toward the contacts.
6. In a snap switch, a support having opposing walls, contacts carried by one of said walls, a substantially U-shaped rocker having flat trunnion portions engaging the support, snap actuating means for said rocker, a transversely extending switch blade on one end of the rocker adjacent said contacts, means for yieldingly urging the blade ends upon said contacts when in engagement therewith with a consequent axial thrust reaction upon the rocker, the trunnion
- opposite the blade end of the rocker having a substantially pointed end where it engages the support.
7. In a snap switch, a support having a cavity therein bounded laterally by substantially parallel walls, bearing recesses formed in said walls, a substantially U-shaped rocker mounted in said cavity, said rocker having trunnions engaged in said recesses, snap actuating means for said rocker, a transversely extending switch blade on the 10 rocker adjacent one of said walls, contacts on said one of said walls for engagement by the blade, means for yieldingly urging the blade ends upon said contacts when in engagement therewith with a consequent axial thrust reaction upon 15 the rocker, the trunnion opposite the blade end of the rocker having its end reduced in cross-sectional area and the recess opposite the blade end of the rocker having a thrust opposing bounding wall adapted to be engaged by the reduced 20 end of the trunnion.
8. In a snap switch, a support having a cavity therein, a substantially U-shaped rocker mounted in said cavity, snap actuating means for said rocker, said cavity having a bounding wall sub- 25 substantially normal to the axis of said rocker, a transversely extending switch blade on the rocker adjacent said wall, a spring member interposed between said rocker and said blade, and contacts on said wall for engagement by the blade 30 ends, the blade ends being yieldably urged toward said wall by said spring member.
9. In a snap switch, a support having a wall, a switch blade adjacent said wall and oscillatable on an axis substantially perpendicular to said 35 wall, means urging said blade toward said wall, stationary contacts outstanding on said wall for engagement by the ends of said blade, and means associated with said wall to lift the blade ends to the contact surfaces as they approach the 40 contacts.
10. In a snap switch, a support providing a wall having an inclined surface, a contact carried by said support, an oscillatory switch blade adapted to engage said contact, snap actuating means 45 for said blade, and means normally axially urging said blade toward said inclined surface, said inclined surface serving to lift said blade to the contact surface of said contact.
11. In a snap switch, a support, a pair of stationary contacts carried thereby, actuating mechanism including a rocker having an axially extending arm provided with a shoulder, a resilient switch blade disposed between said shoulder and contacts, said blade having end contact portions 55 and a central portion fitted on said arm and abutting said shoulder, said central portion being offset toward said shoulder, there being cooperating portions between said rocker and support to take the thrust of the blade transmitted through 60 said shoulder when said contact portions engage said contacts.
12. In a snap switch, a body, stationary contacts on a face presented by said body, a rocker mounted in connection with said body, snap actuating means for said rocker, a switch blade carried by said rocker and having contact portions for cooperation with said contacts, and insulating portions disposed adjacent said contacts and upon which said contact portions ride to be 70 guided onto said contacts, said insulating portions being so arranged as to retard the approach of said contact portions to said contacts.
